UNITED STATES PATENT OFFICE.

EARL G. WATROUS, OF CHICAGO, ILLINOIS.

LAVATORY-FIXTURE.

1,274,646.

Specification of Letters Patent. Patented Aug. 6, 1918.

Application filed September 19, 1914. Serial No. 862,616.

To all whom it may concern:

Be it known that I, EARL G. WATROUS, a citizen of the United States, residing at Chicago, Cook county, Illinois, have invented certain new and useful Improvements in Lavatory-Fixtures, of which the following is a specification.

My invention relates to a lavatory fixture and the object thereof is to improve the construction and operation of such fixture, particularly those of the type in which the valve is normally held closed by spring pressure and opened against such pressure. My invention consists more particularly in the provision of novel and simple means for locking the valve stem and adjusting nut in adjusted position and also in the provision of novel and simple cam means for operating the valve by means of the usual crown handle and for preventing the sticking of the handle which frequently occurs in fixtures of this type. The various features of advantage and utility in my new construction of lavatory fixture will be apparent from the description hereinafter given.

In the drawing Figure 1 is a vertical sectional elevation of a lavatory fixture embodying my invention; Fig. 2 a plan view of the adjusting nut; Fig. 3 a section on the line 3—3 of Fig. 2; Fig. 4 a perspective of a locking plate; Fig. 5 a top plan view of the cam bearing head and Fig. 6 a bottom plan view of the crown handle.

Referring to the particular embodiment of my invention as herein shown, the fixture includes the usual body or casing 1 having the usual inlet port 2 which is governed by a vertically movable valve 3 passing through and guided by the usual deflecting plate or ledge 4. The valve is provided with a vertical stem 5 passing through a bearing head 6 which is screwed into the upper tubular portion of the body or casing 1. This bearing head has a series of cam grooves 6^a which are here three in number, said grooves being deepest at their middle portion and inclining upwardly toward their ends. The head is provided with an upwardly extending shell portion having three inwardly directed ribs 6^b forming stops in coöperation with the crown handle as hereinafter described.

The crown handle 7 consists of a central cylindrical portion and an outer marginal shell portion 7^b adapted to overhang and inclose the tubular portion of the bearing head

6. The bottom of the cylindrical portion is provided with grooves 7^c corresponding to the cam grooves 6^a of the bearing head. These grooves are adapted to receive a series of three balls 8, with the result that when the crown handle is turned in one direction or the other such handle is raised by the action of the balls in riding upwardly upon the inclined cam surfaces of the 65 grooves 6^a. Inasmuch as the valve stem is operatively connected with the crown handle in the manner hereinafter explained, the valve will be opened.

The crown handle can be operated in 70 either direction, that is by turning to the right or to the left, but it is desirable that means be provided for limiting the movement of such handle in either direction and one feature of my invention relates to such 75 means. The stops 6^b, hereinbefore referred to, are three in number corresponding to the number of cam grooves and balls employed and any two of them are adapted to coöperate with the single stop 7^d formed on the 80 exterior of the cylindrical portion of the crown handle and located intermediate two of the grooves 7^c. When the parts are in normal position the stop 7^d is located midway between two of the stops 6^b, with the result 85 that when the handle is turned in one direction the stop 7^d will contact one of these two stops 6^b and when turned in the other direction it will contact the other stop 6^b. The stops 6^b are arranged at the end of 90 radial lines passing through the center of the grooves 6^a so that when the crown handle is turned and the stops are in contact, the handle has reached its extreme position of oscillation and cannot be oscillated 95 any farther by reason of the positive stopping means thus provided. Heretofore when no positive stops were employed and reliance was placed upon the ends of the grooves 6^a for stopping purposes, the balls 100 would ride upon the intervening space between the grooves 6^a and would stick thereon, with the result that the valve would be held open and the water permitted to waste.

The cylindrical portion of the crown 105 handle is provided with a central circular recess into which the outer end of the valve stem 5 extends and which receives the adjusting nut 9. By preference balls 10 acting as bearings are provided between the 110 nut and the bottom of the recess of the crown handle. The nut screws upon the

screw-threaded end of the valve stem whereby the position of the stem and its valve relative to the handle may be adjusted and provision thereby made for the proper seating of the valve in case of wear. The valve stem and crown handle are held in proper relative position by means of the coiled spring 11 which normally holds the valve seated.

- 10 The adjusting nut and valve stem are provided with means for locking them together, constituting another feature of my invention. As shown the valve stem is made tubular at its outer end to receive a 15 coiled spring 12 and such end is provided with diametrically opposite slots 5^a. The adjusting nut has a central counterbore opening, the larger of which is screw threaded to screw upon the screw threads of 20 the outer end of the valve stem and the smaller of which is smooth. The junction between the two bores of the nut forms a shoulder 9^a. In addition the nut is provided on its outer end or top with a transverse slot 9^b adapted to receive a screwdriver or other tool for turning the nut. The slots 5^b of the valve stem receive the locking member which is in the form of a plate 13 wider at its lower end, thereby providing shoulders 13^a on its opposite edges. The narrower portion of this plate extends upwardly through the smaller bore of the nut and into the slot 9^b thereof. This plate is held projected in such normal position as 30 shown in Fig. 1 by means of the coiled spring 12. When in such position the plate locks the adjusting nut and valve stem together, that is prevents any rotation of the nut that would destroy the said adjustment. 35 When, however, it is desired to make a new adjustment the construction is such that the locking device is unlocked as an incident to the act of applying a tool such as a screwdriver to the nut and turning the same. 40 When the screw-driver for instance is inserted in the slot 9^b of the nut it necessarily contacts the upper end of the locking plate 13 which is thereby forced downwardly against the tension of its spring. When the 45 plate has thus been depressed below the plane of this slot the nut is free to be turned in the proper direction for adjustment purposes, and when the tool is removed from the nut and the latter is in such position 50 that its slot 9^b will register with the slots 5^a the locking plate will at once be projected outwardly to locking position by means of its spring. The locking plate 13 is limited or stopped in its upward projection by 55 means of the contact between its shoulders 13^a and the interior shoulders 9^a of the nut. It will be understood that the cavity or recess of the crown handle is closed by the removable plug 14.
- 60 By reason of the provision of the stop

members 6^b and 7^a the movement of the crown handle in both directions is limited, thereby preventing any binding or wedging action of the balls such as frequently occurs in the ordinary construction. When the 70 parts are in normal position the stop member 7^a is midway between two adjacent stop members 6^b so that the handle may be oscillated in either direction but stopped when the member 7^a comes in contact with either 75 one of said two adjacent stops 6^b. By the provision of three equidistantly spaced stops 6^b the crown handle in being assembled may be placed in any one of three positions so that its stop member 7^a will be positioned 80 between any two of the three stops 6^b.

I claim:

1. A lavatory fixture comprising a casing having an inlet port, a valve governing said port and having a stem, means for operating the valve comprising a bearing head mounted on the valve body and having a series of cam grooves and an upwardly extending shell, a crown handle operatively connected with the valve stem and having 90 grooves opposed to said cam grooves and a downwardly extending shell surrounding the shell on the head, balls received by the pairs of grooves, said upwardly extending shell being adapted to receive the body portion of the handle, said body portion being recessed at its upper end to receive the upper end of the valve stem, and an adjusting nut mounted upon such end of the stem and received within the recessed upper end of the 100 handle.

2. A lavatory fixture comprising a casing having an inlet port, a valve governing said port and having a stem, means for operating the valve comprising a bearing head 105 mounted on the valve body and having a series of cam grooves and an upwardly extending shell, a crown handle operatively connected with the valve stem and having grooves opposed to said cam grooves and a 110 downwardly extending shell surrounding the shell on the head, balls received by the pairs of grooves, said upwardly extending shell being adapted to receive the body portion of the handle, said body portion being 115 recessed at its upper end to receive the upper end of the valve stem, an adjusting nut mounted upon such end of the stem and received within the recessed upper end of the handle, and ball bearings between the nut 120 and bottom of such recess.

3. A lavatory fixture comprising a casing having an inlet port, a valve governing said port and having a stem, means for operating the valve comprising a bearing head 125 mounted on the valve body and having a series of cam grooves and an upwardly extending shell, a crown handle operatively connected with the valve stem and having grooves opposed to said cam grooves and a 130

downwardly extending shell surrounding the shell on the head, balls received by the pairs of grooves, said upwardly extending shell being adapted to receive the body portion of the handle, said body portion being recessed at its upper end to receive the upper end of the valve stem, and an adjusting nut mounted upon such end of the stem and received within the recessed upper end of the handle.

4. In a lavatory fixture, the combination with a valve body having an inlet port and a valve governing said port, of means for operating the valve comprising a bearing head on the valve body having a series of cam grooves, a crown handle having grooves opposed to said cam grooves, balls received in the pairs of grooves and operating connections between the handle and valve including ball bearings and coöperating stop lugs on the head and handle respectively, the stop lugs on one of said members being located opposite the middle of the respective cam grooves therein, and the lug on the other member being positioned between two adjacent grooves therein.

5. In a lavatory fixture, the combination with a valve body having an inlet port and a valve governing said port, of means for operating the valve comprising a bearing head on the valve body having a series of cam grooves, a crown handle having grooves opposed to said cam grooves, balls received in the pairs of grooves and operating con-

nections between the handle and valve, including ball bearings, said head having a plurality of inwardly directed projections forming stops opposite each of the grooves therein, and the handle having an outwardly directed projection which is normally positioned midway between two of said stops whereby oscillation of the handle in both directions is limited.

6. In a lavatory fixture, the combination, with a valve body having an inlet port and a valve governing said port, of means for operating the valve comprising a bearing head on the valve body having a series of cam grooves, a crown handle operatively connected with the valve and having grooves opposed to the cam grooves, and balls received in the pairs of grooves, said head having a plurality of inwardly-directed projections forming stops located in radial lines passing transversely through the center of each groove of such head, and the handle having an outwardly directed projection which is located on the handle at a point between the grooves of such handle and which is normally positioned midway between two of said stops whereby the oscillation of the handle in both directions is limited.

EARL G. WATROUS.
